Specification for Design.

Patented Jan. 17, 1922.

Application filed February 9, 1920. Serial No. 357,362. Term of patent 3½ years.

To all whom it may concern:

Be it known that I, ROLLIN H. SPRAGUE, a citizen of the United States, residing at Monroe, in the county of Monroe and State of Michigan, have invented a new, original, and ornamental Design for a Name Stamp, of which the following is a specification, reference being had to the accompanying drawing, forming a part thereof.

The figure is a plan view of a name stamp showing my new design.

I claim:

The ornamental design for a name stamp as shown.
